E. ODELL

OBSTETRICAL DEVICE

Filed Dec. 22, 1925

UNITED STATES PATENT OFFICE.

EDWIN ODELL, OF CENTRAL CITY, NEBRASKA.

OBSTETRICAL DEVICE.

Application filed December 22, 1925. Serial No. 77,012.

This invention relates to an obstetrical device and has for its object to provide a device of this character which may be used to exert a powerful pull upon the baby to effect the delivery without injuring the baby or the mother.

A device embodying the present invention employs a pair of separable handle and carrier members and a pair of flexible gripping members which are preferably soft but have the requisite degree of tensile strength. At their forward ends, the handle and carrier members are provided with eyes and through these eyes the flexible gripping members are threaded. The handle and carrier members are separately inserted on the opposite sides of the baby after the flexible gripping members are threaded therein and after being inserted and properly positioned, the handle and carrier member have their rearward portions brought into cooperative engagement which results in transversely alining the eyes on opposite sides of the baby. As a result of this opposed relation of the eyes at the forward end of the handle and carrier members, the gripping members when drawn taut form encircling loops which firmly grip the baby without danger of slipping and without injuring the baby or mother.

Other objects and advantages reside in certain novel features of the construction, arrangement and combination of parts, which will be hereinafter more fully described and particularly pointed out in the appended claims, reference being had to the accompanying drawings forming a part of the specification and in which:

Figure 1 is a perspective view showing how the flexible members are threaded through the eyes of the handle and carrier member.

Figure 2 is a plan view of the handle and carrier members alone, the gripping members being omitted.

Figure 3 is a fragmentary perspective view showing how the loops are formed, and

Figure 4 is a similar view showing another form or variation of the invention.

Referring to the drawings it will be seen that the obstetrical device embodying the present invention includes a pair of separable handle and carrier members designated generally at 1 and 2 and constructed of

metal or other strong rigid material. The handle and carrier members are in most respects of identical construction and consist of handle portions designated at 3 and 4 respectively and shanks designated at 5 and 6 respectively, the shanks having curved spanning portions 7 and 8 respectively. The curved spanning portions 7 and 8 terminate in eyes 9 and 10 respectively.

The eyes 9 and 10 are of identical form and in one form of construction have their openings of triangular form, the walls of the openings of the eyes being straight and being designated at 9^a, 9^b, and 9^c and 10^a, 10^b and 10^c respectively. In the form of the invention shown in Figures 1, 2 and 3 the eyes are provided with entering slots 11 and 12 for the loops of the flexible grippers. In the form of the invention shown in Figure 4 the entering slots 11 and 12 are omitted and the eyes designated at 13 and 14 present a one piece structure. The openings of the eyes 13 and 14 are preferably round. As shown in Figure 2, the forward portions of the eyes 9 and 10 are turned outwardly. The eyes 13 and 14 are likewise formed.

Flexible grippers designated generally at 15 and 16 are provided, the flexible grippers preferably being in the form of flat wide, textile tape which is soft and flexible and yet substantially inelastic longitudinally as well as possessed of the requisite tensile strength. Other flexible material having the requisite tensile strength may also be employed. The grippers 15 and 16 have attaching loops 17 and 18 respectively, the attaching loops 17 and 18 being engaged with the eyes 9 and 10 respectively. In the form of the invention shown in Figure 1 the attaching loops are formed on the grippers prior to their association with the eyes. Each of the attaching loops may be formed by turning back an end portion of the tape making up a gripper upon the body of the tape and stitching the extremity of such turned back end portions to the body of the tape. The attaching loops 15 and 16 so formed may be engaged with the eyes 9 and 10 in the form of the invention shown in Figures 1, 2, and 3 by passing portions of these attaching loops 17 and 18 through the entering slots 11 and 12 respectively. With the form of the invention shown in Figure 4 the flexible gripper mem-

bers 15 and 16 are formed in the shape of loops and are engaged with the eyes 13 and 14 respectively. The grippers 15 and 16 are attached to the body of the tape by stitching the extremities of the loops to the body of the tape.

bers may be in the form of bandages B and B', or may take any other suitable form but have both ends passed through the eyes and extended rearwardly to be gripped by the hands of the operator or his assistant.

The flexible grippers are threaded through the eyes in such manner that when drawn taut they will form encircling loops.

The preferred mode of threading is shown in Figure 1 and results in the formation of the encircling loops shown in Figure 3.

As illustrated in Figure 1 the free end of the flexible gripper 16 is carried back over the handle and carrier members, then curved around and extended back to a point opposite the eye 9, then threaded through the eye 9 and then extended back to the handle portion 4. The flexible gripper 15 is similarly positioned below the handle members and the extremity of the free end thereof is also held by the operator or his assistant.

After the flexible grippers are threaded through the eyes 9 and 10 in this manner, the handle and carrier members 1 and 2 are separately inserted in the vagina and are properly positioned with respect to the head of the baby. Then the handle portions 3 and 4 are again brought together and the proper positioning of these handle portions relative to each other is facilitated by virtue of the provision of a pin 21 on the handle portion 4 and a socket 22 in the handle portion 3 in which the pin 21 snugly fits. When the pin 21 is engaged in the socket 22 the handle portions 3 and 4 are exactly opposite each other and since the handle and carrier members are identical the eyes 9 and 10 are also exactly opposite or transversely alined. Now then when the free ends of the flexible grippers are drawn taut the loops L and L' which are formed follow the position of these eyes and thus properly encircle and engage the head of the baby.

I claim:

1. An obstetrical device including a pair of separable handle and carrier members of rigid construction and having eyes at their forward ends and flexible grippers, each gripper having one end secured to an eye

and being threaded through the other eye to form an encircling loop.

2. An obstetrical device including a pair of separable handle and carrier members of rigid construction and having eyes at their forward ends and flexible grippers, each gripper having an attaching loop at one end engaged with an eye and being threaded through the other eye to form an encircling loop, said eyes having entering slots for the attaching loops.

3. An obstetrical device including a pair of separable handle and carrier members of rigid construction and having eyes at their forward ends and flexible grippers, each gripper having one end secured to an eye and being threaded through the other eye to form an encircling loop, said handle and carrier members having handle portions provided with means for alining the members and their eyes when the handle portions are brought together.

4. An obstetrical device including a pair of separable handle and carrier members of rigid construction and having eyes at their forward ends and flexible grippers, each gripper having one end secured to an eye and being threaded through the other eye to form an encircling loop, said handle and carrier members having handle portions provided with means for alining the members and their eyes when the handle portions are brought together and consisting of a pin on one handle portion, the other handle portion having a socket receiving said pin.

5. An obstetrical device comprising a pair of separable and unconnected handle and carrier members of rigid construction, the handle and carrier members comprising similar handle portions and similar spanning portions terminating in eyes, and a pair of flexible grippers threaded through said eyes to provide encircling loops, the handle portions being entirely separable to facilitate insertion and manipulation of each member, the handle portions when engaged and transversely alined bringing the eyes into opposed relation.

EDWIN ODELL.
